BOOK COVER

Milfred A. Grout, Springfield, Mass., assignor to Holden
Patent Book Cover Company, Springfield, Mass., a corporation

Application June 6, 1955, Serial No. 36,375

Term of patent 14 years

(Cl. D6—2)

The cover is of sheet material of conventional thickness and the face thereof opposite to that shown is plain and unornamented.

The figure on the drawing is a top plan view of a book cover showing my new design.

I claim:

The ornamental design for a book cover, as shown and described.
